MILK CASE

Leo E. Owen, Seymour, Ind., Clifford C. Fay, Chula Vista,
and Vernor E. Meurer, Fullerton, Calif., and Richard
L. Allman, Seymour, Ind., assignors to Standard Oil
Company, Chicago, Ill.

Filed Nov. 14, 1974, Ser. No. 523,560

Term of patent 14 years

Int. Cl. D9—03

U.S. Cl. D9—177

FIG. 1

FIG. 2

FIG. 3

FIG. 4

FIG. 1 is a side elevational view of a milk case showing our new design, the opposite side being the same in appearance;

FIG. 2 is an end elevational view, the opposite end being the same in appearance;

FIG. 3 is a top plan view; and

FIG. 4 is a bottom plan view.

We claim:

The ornamental design for a milk case, as shown and described.
